UNITED STATES PATENT OFFICE.

MARY HELEN FORSYTH, OF SURREY, ENGLAND.

DESIGN FOR A TABLE FORK.

Application filed September 24, 1927, Serial No. 23,536, and in Great Britain July 26, 1927. Term of patent 7 years.

To all whom it may concern:

Be it known that I, MARY HELEN FORSYTH, a subject of the King of Great Britain and Ireland, residing at Surrey, England, have invented a new, original, and ornamental Design for Table Forks, of which the following is a specification, reference being had to the accompanying drawing, forming part thereof.

I claim:

The ornamental design for a table fork, as shown.

In testimony whereof I affix my signature.

MARY HELEN FORSYTH.
